UNITED STATES PATENT OFFICE.

JAKE M. STIVERS AND ANDREW C. ENOCHS, OF OKLAHOMA, OKLAHOMA.

SHARPENER FOR RAZOR-BLADES.

1,135,633.

Specification of Letters Patent. Patented Apr. 13, 1915.

Application filed January 18, 1915. Serial No. 2,954.

To all whom it may concern:

Be it known that we, JAKE M. STIVERS and ANDREW C. ENOCHS, citizens of the United States, and residents of Oklahoma city, in 5 the county of Oklahoma, and State of Oklahoma, have invented certain new and useful Improvements in Sharpeners for Razor-Blades, of which the following is a specification, reference being had to the annexed 10 drawings.

An object of the invention is to provide a cheap, simple, and convenient device for sharpening razor blades.

One embodiment of the invention in practical form is shown by the accompanying drawings.

Figure 1 is a plan view of the main portion of the improved device. Fig. 2 is a similar view of a clamp in which the blade 20 is held for sharpening. Fig. 3 is a plan view of the device in use. Fig. 4 is an elevation view of the parts shown in Fig. 3.

Referring to the several figures, in all of which like characters of reference designate 25 like parts, the device includes a sheet-metal base 5, arranged to support two small hones 6.

To hold the hones 6 against displacement, small lugs 7 are struck up from the base 30 5 at the inner edges of said hones and similar lugs 8 at their ends, the longer or side edges of the base being flanged upward as at 9 to support the hones in an inwardly tilted position.

The hones 6 are held down securely in 35 place by clamping bars 10, which are in turn held down on said hones by small bolts 11 that pass up through the base 5 and said bars and are provided with nuts 12.

In further arrangement, a clamp for holding the blade 13 is composed of two metal 40 bars or blocks 14 between which the blade is clamped, these bars being held to said blade by small bolts 15 which pass removably 45 through them and said blade and are provided with nuts 16.

In use, the blade 13, held between the bars 14, is placed with one of its cutting edges

17 on one of the hones 6 and its other cutting edge on the other hone, the lower clamping 50 bar 14 filling the space between the hones 6 with just a sliding clearance and being guided by said hones during the longitudinal sliding movement of the blade thereon.

The sliding movement of the blade 13 55 on the hones 6 is properly limited by lugs 18 which are struck up from the ends of the base 5 into the path of movement of the lower bar 14, and by giving the blade a few sliding movements on the hones in the direction shown, it may be quickly sharpened to a shaving edge or to a condition to be finished by stropping.

Having thus described the invention, we 65 claim:

1. In a device of the class described, a base, hones supported on the base side by side and tilted toward each other thereon, and means for guiding a blade in its sliding movement on said hones. 70

2. In a device of the class described, a base, hones mounted on the base and spaced apart thereon, bars resting on the hones to hold them in place, bolts passing up through the base and through said bars to hold said 75 bars to the hones, and means for guiding a blade in a sliding movement on said hones.

3. In a device of the class described, a base, hones mounted on the base and spaced apart thereon, bars resting on the hones to 80 clamp them in place, bolts passing up through the base and through said bars to hold the bars to the hones, a clamping device comprising two bars adapted to engage opposite faces of a blade, said device 85 being adapted to project down between the edges of the hones and be guided thereby during sliding movements of the blade on said hones.

Witness our hands this 16th day of January, 1915.

JAKE M. STIVERS.
ANDREW C. ENOCHS.

Witnesses:

J. P. MOSS,
GEO. C. HADEN.
